UNITED STATES PATENT OFFICE

DE FOREST ROE, OF ELYRIA, OHIO, ASSIGNOR TO THE COLSON COMPANY, OF CLEVELAND,
OHIO, A CORPORATION OF OHIO

BUFFER

Application filed May 10, 1929. Serial No. 361,875.

My invention relates to buffers for furniture legs, and relates more particularly to annular rubber buffers adapted to be used on bed legs.

5 An object of my invention is to provide a rubber buffer adapted to be secured to the legs of a bed to prevent the bed from marring furniture, base boards and the like when pushed about the room.

10 Another object of my invention is to provide a buffer for a bed which acts as a shock absorber, eliminating the jolts which are ordinarily had by a patient when the bed is moved about or when a truck or the like 15 bumps against the leg of the bed.

Another object of my invention is to provide a buffer adapted to fit and to be secured to different sizes of legs.

Another object of my invention is to provide a buffer which will remain securely in place when fastened to the legs of an article of furniture and not be easily displaced.

Another object of my invention is to provide a buffer of simple and economical construction which may be applied laterally to the leg of an article of furniture, to encircle it, thus obviating lifting of the bed which would otherwise be necessary.

Other objects of my invention and the invention itself will become apparent by reference to the following description of an embodiment of my invention illustrated and described herein.

Referring to the drawings:

25 Fig. 1 is a perspective view of a bed with buffers embodying my invention secured to the legs thereof.

Fig. 2 is a plan view of the buffer being 40 applied to a furniture leg.

Fig. 3 is a plan view of the buffer on a furniture leg partially drawn into position.

Fig. 4 is a plan view of the buffer of Figures 2 and 3 tightly clamped upon a furniture leg.

Fig. 5 is a plan view of another embodiment of my invention.

Fig. 6 is a plan view of still another embodiment, certain parts being broken away, 50 and shown in section.

Fig. 7 is an elevational view of the buffer of Fig. 6.

Fig. 8 is a vertical, medial, sectional view of the buffer of Fig. 4.

Fig. 9 is a vertical medial, sectional view 65 of the buffer of Fig. 6.

Referring to the figures of the drawings wherein like parts are designated by like reference characters, my buffer comprises generally a rubber annulus 2 divided at 3 60 and having a central bore 4.

A C-shaped metallic strip 5 of rectangular cross-section is disposed in the annulus about the bore 4 and is provided with ends 6 and 7, one end 6 being screw threaded 65 at 8, and the other end provided with an aperture 9. An engaged aperture 10 is disposed in the annulus extending from the metallic end 7 to the periphery of the annulus, being adapted to permit access to the 70 aperture 9 in the metallic insert.

An aperture of smaller diameter 11 is provided, which extends from the other side of the metallic insert 7, communicating with the divided portion of the annulus. A 75 smaller aperture 12 is provided, which communicates with the insert which is in the opposite direction of the annulus and a recess 13 is disposed on the opposite side of the metallic insert 6. The apertures 10, 11, 80 12 and 13 in the annulus and the apertures 8 and 9 in the insert are in axial alignment adapted to receive therein a screw 14 for drawing the divided ends of the annulus closely together when the screw is tightened 85 in the insert end 6.

As best shown in Figs. 8 and 9, the walls of the bore 4 are of gradually diminishing area from a point 15 proceeding from the middle of the annulus towards both ends 16 90 of the bore.

Furniture legs, especially on hospital beds and the like, are usually of a standard construction, being of square or round cross section such as shown in Figs. 3 and 5. In 95 applying the annulus of my invention as best shown in Figs. 2 and 4, the annulus is spread apart as shown in Fig. 2 and disposed about the leg 17 until the leg centers in the aperture bore 4. The split walls of 100

the annulus 3 will then spring together and the bolt 14 may be screwed into the aperture 8 until the ends of the metallic loop or clamp are drawn towards each other as shown in Fig. 3, carrying with it the rubber body of the annulus. The bolt may be tightened until the faces of the split portions of the annulus are drawn tightly together. The resiliency of the material and the shape 10 of the bore will permit the annulus to be disposed about legs of various sizes.

In Fig. 6 I have more particularly shown a buffer adapted for use on square legs. The buffer of Fig. 5 is more especially 15 adapted for substantially square legs of the type having a ridge or ribbed portion running up the pair of the sides commonly known as grace line. The buffer of Figs. 2, 3 and 4 is adapted for round legs such as 20 shown in Fig. 1.

Having thus described my invention in a preferred embodiment I am aware that numerous and extensive departures may be 25 made from the embodiment herein illustrated and described but without departing from the spirit of my invention.

I claim:

1. A buffer for furniture legs comprising a rubber annulus of substantial thickness 30 divided transversely at one point of its length and having an interior bore of gradually diminishing transverse area proceeding from the middle toward both ends of the bore.

35 2. A buffer element for furniture legs, comprising a split rubber annulus of substantial thickness constructed to be inherently contractible to tightly grip the leg with the inner wall of the annulus in resilient compressive contact therewith, said inner 40 wall extending divergently from the two ends of the annulus to its interiorly disposed middle portions.

45 3. In a buffer for furniture or like legs, a split rubber annulus having a longitudinal bore, a split metal band in the form of a loop embodied within the annulus and embracing the longitudinal bore thereof, means engaging the two ends of the band 50 adapted to draw them and the divided rubber annulus edges together to contractively grip an encircled leg, the bore being of gradually increasing transverse area proceeding from the ends of the bore interiorly thereof.

55 4. In a buffer for the legs of furniture or the like, a split rubber annulus, a split metal band embodied in the annulus and embracing the bore thereof, means adapted 60 to engage the ends of the band and to draw them toward each other to draw the annulus together at the split portion thereof to contractingly grip an encircled leg.

65 5. In a buffer for the legs of furniture or the like, a split rubber annulus, a generally

70 C-shaped strip of metal embedded within the material of the annulus and with the ends thereof disposed adjacent the confronting ends of the annulus at the split portions thereof, and a screw-threaded element adapted to engage the ends of the strip and draw them toward each other to clamp the annulus on an encircled leg.

75 6. In a buffer for the legs of furniture or the like, a split rubber annulus, a generally C-shaped strip of metal embedded within the material of the annulus and with the ends thereof disposed adjacent the confronting ends of the annulus at the split portions thereof, and a screw-threaded element 80 adapted to engage the ends of the strip and draw them toward each other to clamp the annulus on an encircled leg, said screw-threaded means being disposed entirely within the exterior surface of the annulus 85 when in said clamped position.

90 7. In a buffer for furniture or like legs, a split rubber annulus, means entirely embedded within the annulus for drawing the divided rubber annulus edges together to contractively grip an encircled leg, the annulus bore being of gradually increasing transverse area proceeding from the ends 95 of the bore interiorly thereof.

95 8. In a buffer for furniture or like legs, a split rubber annulus, means entirely embedded within the annulus for drawing the adjacent end portions of the divided annulus toward each other to contractively grip an encircled leg, the embedded means comprising a threaded nut element adjacent one annulus end portion, a perforated washer element adjacent the other annulus end portion, and a screw projected through the perforation and engaging the washer by a head 100 portion thereof and screwed into the threaded nut element.

105 In testimony whereof I hereunto affix my signature this 8th day of May, 1929.

DE FOREST ROE.
